(57) **CLAIM**

The ornamental design for a personal grooming bar as shown and described.

DESCRIPTION

FIG. 1 is a front view of a personal grooming bar in accordance with our new design; and,

FIG. 2 is a side view of the personal grooming bar shown in FIG. 1.

The claimed design extends up to the dash-dot boundary line but does not include the boundary line. The evenly-spaced broken lines illustrate portions of the personal grooming bar and form no part of the claimed design.
